UNITED STATES PATENT OFFICE.

GEORGE YEAGER, OF BAY CITY, TEXAS.

TANK-FURNACE.

1,248,050.

Specification of Letters Patent. Patented Nov. 27, 1917.

Application filed August 4, 1914. Serial No. 855,008.

To all whom it may concern:

Be it known that I, GEORGE YEAGER, a citizen of the United States, residing at Bay City, in the county of Matagorda and State 5 of Texas, have invented certain new and useful Improvements in Tank-Furnaces, of which the following is a specification.

This invention relates to water heaters, and more particularly to a furnace which is 10 particularly adapted for use in connection therewith, and also relates to an improvement in a tank which is adapted for use in connection with the furnace.

The object of my invention is to provide 15 a water heater as above described which is adapted to receive a water tank upon the furnace structure thereof, and heat the water in the tank.

Another object of my invention is to provide 20 a device of this character which may be used in the open air and which is particularly adapted for use as a camp water heater.

A still further object of my invention is 25 to provide a water heater which has a simple and effective means associated therewith for facilitating a rapid heating of the water in a tank.

A still further object of my invention is 30 to provide means for preventing the contents of the tank from becoming burned, due to contact with the bottom thereof.

My invention resides in the construction, 35 combination and arrangement of parts as more fully set forth hereinafter in the specification and illustrated in the accompanying drawings, in which:—

Figure 1 is a side elevation of a water heater in which the preferred embodiment 40 of my invention is illustrated.

Fig. 2 is a longitudinal sectional view of the same, and

Fig. 3 is a detail section on line 3—3 of Fig. 2.

Similar reference characters indicate similar parts throughout the various views of the drawings.

Referring more particularly to the drawings in which the preferred embodiment of 50 my invention is illustrated, I provide a base 1 which comprises the furnace structure, the top and bottom of the same being open, and a tank 2, which may be a wash boiler or a cooking utensil is supported upon a top opening of the base or furnace 1, a ledge 55 or shelf 3 being provided upon the upper

marginal edge of the said base 1 and the tank 2 adapted to be seated or placed thereon. A transverse rod 3' extends across the furnace substantially intermediate its ends 60 for the purpose of preventing expansion of the same when a fire is started therein. A band 4 is secured to the outer surface of the furnace 1 by bolts or other suitable means 65 4' as is shown to advantage in Figs. 1 and 2. The band, at the point at which it engages the furnace 1, is flared outwardly so as to conform to the slanting sides of said furnace 1, the upper portion of said band 4 being vertical for engagement with the base 70 of the tank 2, said band 4 extending slightly above the ledge 3, to provide a means for preventing lateral displacement of the tank 2. The furnace 1 is provided with the usual door 5 and draft opening 6, and is 75 adapted to be placed upon the ground or earth, the earth forming the base of the same upon which to start a fire. The products of combustion are carried off from the furnace through a chimney 7 extending from 80 one end of said furnace 1.

The tank 2 is provided with a cover 8 or other suitable closure, and a protecting plate 9 is provided in the interior of the tank 2 and supported in spaced relation to the bottom 2' of said tank 2 by means of the downturned edge 10 thereof. The protecting plate 9 is similar in configuration to the tank 2 and is arranged to fit snugly within the tank as shown in Fig. 2. Openings 11 90 in the plate 9 allow the liquid in the tank to circulate over and under the plate 9.

The tank 2 is provided with a longitudinally extending conduit 12, said conduit 12 being in communication with the chimney 7 35 by means of a downwardly extending tubular portion 13 whereby to receive the products of combustion from the chimney of the furnace 1 and convey the same through the conduit 12 and out through the chimney portion 14 thereof, this conduit 12 providing an additional means for heating the contents of the tank 2.

As is shown to advantage in Fig. 2 the protecting plate 9 rests upon the conduit 12, said conduit 12 serving as a means for supporting the central portion of said plate, and preventing the bending of the same, as well as serving as a means for facilitating the heating of the water in the tank. From Fig. 2 the course of the products of combustion and heat will be readily noted, as the

chimney 7 is connected with the furnace 1 and communicates therewith by means of a tubular member 7', and the products of combustion leave the furnace 1 by the tubular member 7', passing up through the tubular connection 13 to the conduit 12, through which the heat and products of combustion will pass to the outer end thereof and through the chimney portion 14 to the outside atmosphere. The bottom 2' of the tank 2, as will be readily seen from Fig. 2, is exposed to the full heat of the furnace 1, and the smoke and other products of combustion pass through the conduit 12 and assist the main portion of the furnace in heating the water or other liquid in the tank 2.

When it is desired to boil the water in the tank a fire is started in the furnace 1 and in a short while it will be found that the water 20 has been brought up to the boiling point. The protecting plate 9 will protect any articles which are in the tank 2, as in the case of a wash boiler the clothes which would be in the tank, from burning, due to contact 25 with the bottom 2' of the tank 2.

The door 5 in the furnace 1 allows of easy access to the interior of the furnace 1 and the openings 6 below the door 5 provide draft openings with which to supply 30 oxygen to the fire.

From the above it is thought that it will be readily appreciated that I have provided a simple, cheap and durable furnace for heating water in a tank, it being readily 35 seen that the type of tank used is not necessarily of the type which I have shown in the drawings as any ordinary wash boiler or tank which is the correct size will fit the opening in the top of the furnace 1, how-

ever, it is preferable that the tank should 40 be made in the form which I have illustrated in the drawings as it is found that this is a very advantageous structure when used in connection with my improved furnace. The portions 13 and 7 are readily detachable so that the tank and the furnace 45 may be readily detached one from the other to allow of emptying the tank or for moving the same from place to place.

While I have shown a specific form of 50 construction for my invention, it will be readily understood by those skilled in the art that certain minor changes in the details of construction thereof may be made without departing from the spirit and scope of 55 the invention hereinafter claimed.

Having thus described my invention, what I claim and desire to secure by Letters Patent is:

In a combined furnace structure and tank, 60 an outlet for the furnace extending exteriorly thereof below the bottom of the tank, a conduit in the tank in spaced relation to the bottom thereof, said conduit having a right angular extension downwardly 65 projecting for detachable engagement with the furnace outlet, and means for preventing accidental lateral displacement of said tank from said furnace, said conduit serving to conduct the products of combustion 70 from the furnace through the tank to heat the contents thereof.

In testimony whereof I affix my signature in presence of two witnesses.

GEORGE YEAGER.
